ATTORNEYS.

UNITED STATES PATENT OFFICE.

HARRY S. FORST, OF PHILADELPHIA, PENNSYLVANIA, ASSIGNOR TO HUGO BAROL,
OF PHILADELPHIA, PENNSYLVANIA.

COMBINATION HAT CARRIER AND OVERNIGHT BAG.

Application filed November 8, 1923. Serial No. 673,425.

To all whom it may concern:

Be it known that I, HARRY S. FORST, a citizen of the United States, residing in the city and county of Philadelphia, State of Pennsylvania, have invented a new and useful Combination Hat Carrier and Overnight Bag, of which the following is a specification.

My invention consists of a hat carrier and an overnight bag which is formed of a body adapted for the reception of a hat and having a rounded bottom so that the general rounded shape of the hat conforms thereto, whereby said shape may be preserved and the hat may be packed against shifting and injury, provision being also made for carrying wearing apparel, toilet and other articles and sufficient requisites for overnight or week end purposes.

The invention is satisfactorily illustrated in the accompanying drawing, but the important instrumentalities thereof may be varied, and so it is to be understood that the invention is not limited to the specific details shown and described, as long as they are within the spirit or scope of the claims.

Figure 1 represents a perspective view of a hat carrier and overnight bag embodying my invention, the body of the same being open.

Figure 2 represents a central vertical section thereof on line 2—2 Figure 1.

Similar numerals of reference indicate corresponding parts in the figures.

Referring to the drawings.

1 designates the body of the hat carrier and overnight bag, the same being formed of comparatively vertical front, rear and side walls, and a bottom 2 which is half round downwardly so as to conform in general respects to the rounded shape of a hat which is placed sideways in the body and conveniently carried thereon without injury thereto, it being evident that a night shirt or some other apparel or article required for travelling may be folded around the hat and rested on the bottom and so pack the hat against shifting and provide a cushion on which the hat may be softly supported and so the hat preserved in shape and condition.

The top of the body which is open is of quadrilateral form and so may receive light articles which may be placed loosely on the hat without damaging it, and assist in packing it from above.

The body has connected with it the lid 3 for closing the top thereof, the same having connected with it the flap 4 which may be locked or fastened to an adjacent portion of the body by snap fastenings, straps and buckles as desired, said lid having thereon a handle 5 for evident purposes.

To the inner side of the lid are secured the pockets 6 for containing articles of use for a traveller, and holders 7 for a comb, tooth brush, button hook and a nail file or other toilet requirements of the kind.

To an inner wall of the body are secured the pockets 8 for containing handkerchiefs, stockings, and other articles of use for a traveller.

It will be seen that I provide a unitary device which is of simple, light and inexpensive construction, compact in its nature and most serviceable for the purpose intended.

Having thus described my invention what I claim is new and desire to secure by Letters Patent, is—

1. A hat carrier and overnight bag consisting of a body having front and rear walls which are flat and which are arranged in parallelism, and side walls which are flat for a portion of their extent and which terminate in a rounded bottom, a flat covering lid, and a foldable flap on the lid with means for fastening the lid to the body, said body having on an inner side thereof receiving pockets for travelling convenience.

2. A hat carrier and overnight bag consisting of a body having front and rear walls which are flat and which are arranged in parallelism, and side walls which are flat for a portion of their extent and which terminate in a rounded bottom, a flat covering lid, and a foldable flap on the lid with means for fastening the lid to the body, said lid having on its underside attached thereto receiving pockets for travelling conveniences.

3. A bag of the character stated having a flat front wall the bottom edge of which is

formed upon a curved line, a flat rear wall
the bottom edge of which is also formed
upon a curved line and the top edge of
which rear wall is provided with a cover
5 having a flap overlying the top edge of said
front wall, side walls the outermost parts of
which are flat, said flat portions terminating

in a curved portion coextensive with the said
curved parts of the front and rear walls to
provide a curved bottom, means for detach- 10
ably securing said covering to place, and a
handle carried by said cover.

HARRY S. FORST.
